UNITED STATES PATENT OFFICE

KARL MAIER, OF STUTTGART, GERMANY, ASSIGNOR TO UNION SPECIAL MASCHINEN-FABRIK, G. M. B. H., OF STUTTGART, GERMANY

FABRIC GUIDE SUPPORT FOR SEWING MACHINES

Application filed September 28, 1926, Serial No. 138,203, and in Germany October 19, 1925.

The invention relates to new and useful improvements in fabric guide supports for sewing machines, and more particularly to a fabric guide support which is so constructed that the fabric guide may be moved away from the stitching point to inactive position in order to give access to the complementary stitch forming mechanism beneath the work support.

5 An object of the invention is to provide a support for a fabric guide which is so constructed that when the fabric guide is moved laterally away from the stitching point, it is also simultaneously raised from the work support.

10 A further object of the invention is to provide a fabric guide support of the above type with a yielding latching means for holding said guide in normal or operative position.

15 A still further object of the invention is to provide a fabric guide support of the above type wherein the fabric guide is so mounted on its support that it may be raised and lowered or adjusted bodily toward and from the stitching line for properly setting the guide relatively to the needle of the stitching mechanism.

20 A still further object of the invention is to provide a fabric guide support of the above character which is so mounted on the work support that it may be bodily adjusted toward and from the rear edge of the machine.

25 These and other objects will in part be 35 obvious and will in part be hereinafter more fully disclosed.

In the drawings:—

Figure 1 is a front view of a sewing machine having the improvements applied 40 thereto;

Fig. 2 is a plan view of the work support, showing the fabric guide support and the fabric guide in top plan view, and with the guide in normal position relative to the 45 needle;

Fig. 3 is a view similar to Fig. 2, but showing the fabric guide as moved away from the needle;

Fig. 4 is a sectional view on the line A—B 50 of Fig. 2;

Fig. 5 is a sectional view showing a modified form of means for raising and lowering the support as it is moved away from and toward the needle; and

Fig. 6 is a sectional view of the parts 55 shown in Fig. 5.

The invention is directed broadly to a fabric guide support for sewing machines, and by a fabric guide is meant any form of device which may be used for guiding the parts to 60 be stitched to the stitching mechanism. There has been shown in the drawings, a fabric guide of the English binder type wherein a binding strip passes through the guide, and this binding strip is inverted and properly 65 positioned relatively to the body fabric for being stitched thereto. This binding guide shown in the drawings, is mounted on a support pivoted to the cloth plate, so that the fabric guide may be moved laterally away 70 from the stitching point to give access to the looper. The support for the guide is so mounted that when it is moved laterally, it gradually raises away from the work support. Several different forms are shown for 75 accomplishing this result. One consists of a supporting bracket having the upper face thereof inclined, so that when the support for the fabric guide slides along the inclined support, it will be gradually lifted away 80 from the cloth plate. Another form of the invention consists in the provision of a spiral groove in the supporting stud, and the utilizing of a pin carried by the support for the fabric guide for causing the fabric guide to 85 be lifted as the pin travels along the spiral groove. The fabric guide is held in normal position close to the needle by a yielding latch. The guide proper is mounted on its support in such a way that it may be adjusted 90 vertically relative to the support, or lengthwise of itself relatively to the support, and the support for the guide is so mounted on the work support, that it may be adjusted 95 toward and from the rear of the machine.

Referring more in detail to the drawings, a sewing machine *b* is shown which is provided with a work support *a*. Mounted on the work support is a fabric guide *c*, which, as above noted, may be of any desired construction. 103

In the present illustrated embodiment of the invention, this fabric guide is in the form of an English binder, which receives a tape or binding *d* led into the receiving end *e* of the guide, and the binding is folded intermediate its edges and is reversed as it passes from the delivering end *f* of the guide, so that the binding may be stitched to a fabric by a stitching mechanism which includes a needle *g*. The body fabric is preferably directed by an edge guide *o* which is attached to the work support in front of the stitching mechanism. In order that the fabric guide may be moved away from the stitching mechanism to give access to the looper, said guide is mounted on a support *h* which is in turn mounted on a pivot *i* carried by a bracket *k* which in turn is secured to the work support by screws *k'*, *k'*. These screws pass through suitable slots in the bracket *k*, and permit the bracket to be adjusted transversely of the cloth plate toward and from the rear edge of the cloth plate. The fabric guide *c* is attached to the holder *h* by means of an angle bracket plate *s*. Said angle plate is provided with slots *u*, *u* and screws *t*, *t* passing through these slots secure the angle plate *s* to the holder. This angle plate *s* has a vertical portion *p* provided with vertical slots *r* through which screws *q* pass. By loosening the screws *q* the guide may be raised and lowered vertically relative to the holder. By loosening the screws *t*, *t*, the guide may be shifted bodily in a direction of its length, or toward and from the line of feed. These adjustments permit the guide to be properly mounted on the holder or support therefor. The bracket *k* as clearly shown in Fig. 4 of the drawings, has its upper face inclined, and the holder or support for the fabric guide is mounted on this upper inclined surface of the bracket. The parts are so shaped and positioned that when the fabric guide is in the position shown in Fig. 2, it is positioned relative to the work support so as to properly guide and direct the strip passing through the guide beneath the presser foot and about the edge of the body fabric. When it is desired to get close to the looper, the support for the fabric guide is swung about its pivot *i* and as the guide moves laterally away from the needle, it will, on account of the inclined upper surface of the bracket *k*, be gradually raised away from the work support. Thus it is that the guide is lifted when it is moved laterally, and this gives a very free movement of the guide so that it is not in any way obstructed by any of the parts of the work support. By the arrangement just described the guide or folder may be readily placed in the usual opening through the cloth plate whereby access is had to the looper for threading the same. The guide may be placed in this opening with its longitudinal center plane substantially in the plane of the work sup-

port, that is, the upper surface of the work support. In cases where an English binder is used, as shown in the drawings, the upper half of the binder is above the plane of the work support and the lower half of the binder is below the plane of the work support, lying in the opening directly over the looper and usually closed by a cover plate. This is the normal operative position of the guide. When it is desired to get access to the looper for threading, the guide is moved away from the stitching point and the supporting means is so constructed that as it moves away it also moves upward out of the opening and to a position above the work support. This completely uncovers the looper so that it may be readily threaded. The support for the fabric guide is yieldingly held in its normal operative position. This is accomplished by means of a pin *v* and a spring latch *y* which is provided with an opening *w* adapted to engage the pin *v*. This latch has a finger piece *x* whereby the latch may be readily raised to release the latch from the pin. When the fabric guide is moved to normal operative position, the pin will automatically lift the spring and engage the opening *w* so as to lock the guide in this position. The latch is raised by the finger piece *x* so that the guide can be swung to inactive position.

In Figures 5 and 6, there is shown a modified means for mounting the support for the fabric guide so that it will be raised from the work support when moved laterally. In this form of the invention, the bracket *k* is done away with, and a post *l* substituted for the pivot pin *i*. This post is provided with a spiral groove *m*. The holder or support *h* for the fabric guide carries a pin *n* engaging the spiral groove. When the holder or support swings about the post *l* as indicated by the arrow *D*, then the pin *n* following the groove will raise the holder away from the cloth plate.

Other means may be provided than those illustrated for lifting the holder or support for the fabric guide away from the work support when it is moved laterally away from the needle, and for returning it to its proper position relative to the work support when it is moved back again into normal operative position.

While the binder guide has been shown in detail, it is understood, of course, that other forms of fabric guides may be used, such as hemmers or the like, as the invention is more particularly in the support for the guide and the manner of raising and lowering the same as it is moved laterally away from and toward the stitching point.

It is obvious that minor changes in the details of construction may be made without departing from the spirit of the invention as set forth in the appended claim.

Having thus described the invention, what

I claim as new and desire to secure by Letters Patent, is:—

In a sewing machine the combination of a work support, a stitch forming mechanism, a fabric guide normally disposed adjacent said stitch forming mechanism in an opening in said work support and with its longitudinal center plane lying in the plane of the work support, and supporting devices for said fabric guide including means whereby the fabric guide may be moved away from the stitching point in a direction obliquely to the plane of the work support whereby said guide is moved to an inoperative position above the plane of the work support for rendering the stitching element beneath the work support accessible for threading through said opening.

10 fabric guide including means whereby the fabric guide may be moved away from the stitching point in a direction obliquely to the plane of the work support whereby said guide is moved to an inoperative position above the plane of the work support for rendering the stitching element beneath the work support accessible for threading through said opening.

15 fabric guide including means whereby the fabric guide may be moved away from the stitching point in a direction obliquely to the plane of the work support whereby said guide is moved to an inoperative position above the plane of the work support for rendering the stitching element beneath the work support accessible for threading through said opening.

20 In testimony whereof, I affix my signature.
KARL MAIER.
